UNITED STATES PATENT OFFICE

AMOS E. NORTHUP, OF PLEASANT RIDGE, MICHIGAN, ASSIGNOR TO REO MOTOR CAR COMPANY, A CORPORATION

DESIGN FOR A RADIATOR

Application filed October 15, 1931. Serial No. 41,402. Term of patent 7 years.

To all whom it may concern:

Be it known that I, AMOS E. NORTHUP, a citizen of the United States, residing at Pleasant Ridge, in the county of Oakland and State of Michigan, have invented a new, original, and ornamental Design for Radiators, of which the following is a specification, reference being had to the accompanying drawings, forming a part thereof.

Fig. 1 is a plan view of a radiator embodying my new design.

Fig. 2 is a front elevation of the radiator shown in Fig. 1.

Fig. 3 is a side elevation of the radiator shown in the previous views.

Fig. 4 is a perspective view of the radiator shown in the previous views.

Fig. 5 is an enlarged fragmentary sectional view taken in a vertical plane passing longitudinally through the radiator centrally thereof, showing the contour of the beading surrounding the core opening in the shell at the upper edge of the opening, the ornament not being shown.

Fig. 6 is an enlarged sectional view taken on the line 6—6 of Fig. 2.

Fig. 7 is an enlarged sectional view taken on the line 7—7 of Fig. 2.

I claim:

The ornamental design for a radiator, as shown.

AMOS E. NORTHUP.
